Patented Aug. 21, 1917.

3 SHEETS—SHEET 3.

UNITED STATES PATENT OFFICE.

FRANK M. PIERCE, OF CHICAGO, ILLINOIS, ASSIGNOR TO PIERCE WRAPPING MACHINE COMPANY, OF CHICAGO, ILLINOIS, A CORPORATION OF ILLINOIS.

GUIDING DEVICE FOR WRAPPING-MACHINES.

1,237,810.

Specification of Letters Patent. Patented Aug. 21, 1917.

Original application filed November 26, 1915, Serial No. 63,502. Divided and this application filed February 21, 1916. Serial No. 79,618.

To all whom it may concern:

Be it known that I, FRANK M. PIERCE, a citizen of the United States, and a resident of the city of Chicago, in the county of Cook and State of Illinois, have invented certain new and useful Improvements in Guiding Devices for Wrapping-Machines; and I do hereby declare that the following is a full, clear, and exact description of the same, reference being had to the accompanying drawings, and to the numerals of reference marked thereon, which form a part of this specification.

This invention constitutes a division of my co-pending application for "double wrapper wrapping machines," filed November 26th, 1915, Serial No. 63,502.

This invention relates to an automatic guiding or centralizing means for articles such as annular objects, particularly coils of wire or tires, placed in a wrapping machine to receive one or more wrappers applied thereon. By this invention an annular object mounted in upright position in a wrapping machine is positively guided and centralized at its upper portion by mechanisms embodying the principles of my invention which are automatically adjustable for articles of different size.

It is an object therefore of this invention to provide a guiding and centralizing device automatically adjustable for articles of different size to maintain the same properly positioned in the wrapping machine during a wrapping operation.

It is furthermore an important object of this invention to construct a pivotally mounted counterweighted guiding and centralizing means for an article being wrapped in a wrapping machine which is automatically adjustable for different articles and as well self-adjusting to compensate for the increasing diameter of an article as a wrapper is applied thereto to maintain the article properly positioned in the machine throughout the wrapping operation.

It is finally an object of this invention to construct a simple automatically acting guiding mechanism for an article in a wrapping

machine serving effectually to maintain an article in proper position while revolved or otherwise advanced in the machine during the wrapping operation.

The invention (in a preferred form) is illustrated in the drawings and hereinafter more fully described.

In the drawings:

Figure 1 is a front elevation of a wrapping machine equipped with a device embodying the principles of my invention. 60

Fig. 2 is a central vertical section taken through the machine, with parts shown in elevation.

Fig. 3 is a top plan view of the guiding device detached from the machine. 65

Fig. 4 is a detail section taken on line 4-4 of Fig. 2, with parts omitted.

Fig. 5 is a fragmentary top plan view of the device, with parts omitted.

Fig. 6 is a top plan view of the counterweight detached from the guiding mechanism. 70

Fig. 7 is a rear end view of the mechanism shown in Fig. 3, with the weight detached.

Fig. 8 is a section taken on line 8-8 of Fig. 3. 75

As shown in the drawings:

The frame of the wrapping machine is denoted as a whole by the reference numeral 1, and is provided with an arched cross member 2, at the upper end thereof. The frame 1, is provided with upright guide rods or posts 3, on which brackets 4, are slidably mounted for vertical adjustment, and journaled in said brackets are supporting and driving rollers 5, upon which an article 6, such as a tire, coil of wire, or other annular object, is placed and supported for wrapping. The details of construction and operation of the mechanisms by which the tire or other object is supported and adjusted, are not entered into further than the brief description in the foregoing. 85 90

Held rigidly in the upper portion of the frame of the machine is a crescent shaped or open gap frame 7, provided with a plurality of rollers 8, and journaled to rotate around said frame upon the rollers is an

open gap shuttle 9. Rotation of the shuttle 9, through the eye of the annular object 6, serves to apply a wrapper upon the article, the strip of wrapping material being drawn from a supply reel 10, mounted upon the shuttle, and moving therewith, thence through a tension device 11, then around an idler roller 12, and finally through a folder plate 13, from which it leads to the article 10 for application thereon.

For the purpose of maintaining the article being wrapped properly centralized through the eye of the shuttle and guiding the article as it is rotated by the machine, 15 a guiding means is provided comprising three rollers 14, arranged in angled relation with one another, as shown in Figs. 1, 7, and 8, journaled or pivoted in a bracket 15, secured upon a lever 16, by means of a bolt 17, adapted to engage through an aperture 18, provided in said lever. Said lever 16, is pivoted at its rear end upon a rearwardly extending bracket 19, bolted to the arched cross member 2, of the wrapping machine frame.

Formed integrally on said lever 16, on each side thereof near the middle of said lever, are upwardly extending plates 20, which extend on each side of the bracket 19, 30 thereby guiding said lever 16, in its pivotal movement, and a pin or bolt 21, is removably secured between said upright plates 20, in any one of a number of registering apertures 22, to limit the downward movement 35 or adjustment of said lever 16, as desired. As clearly shown in Figs. 2 and 5, the upper surface of the rear end of said lever 16, is provided with a series of notches denoted by the reference numeral 23, which 40 are formed in a central longitudinal rib on the surface of said lever, and a weight 24, having upwardly directed wing extensions 25, is adapted to be suspended on said lever by means of a pin 26, engaging through 45 said wing extensions of the weight and seating in one of the notches 23, of the lever. Said weight is provided with a forwardly directed projection or extension 27, which bears upwardly beneath the under surface 50 of said lever 16, to brace the weight in its attached position on said lever.

In operation, the rollers 14, rest upon the periphery of the article 6, being wrapped, and, due to the weight 24, attached on the 55 lever on which said rollers are mounted, the same are brought to bear with a predetermined pressure upon the periphery of the object. Due to the angled relation of said rollers, they engage not only on the 60 extreme outer periphery of the object, but also downwardly on each side thereof, thus guiding and centralizing the object, particularly at the point at which the wrapper is applied thereto by the shuttle. The pres-

sure with which the rollers are brought to 65 bear upon the article may be varied by shifting the weight 25, along on the pivoted lever 16. In order to limit the downward movement of said lever as the same swings down by gravity, the upwardly extending 70 plates 20, are provided with the stop pin 21, adjustable therein at different points to limit this movement to different amounts.

I am aware that various details of construction may be varied through a wide 75 range without departing from the principles of this invention, and I therefore do not purpose limiting the patent granted otherwise than necessitated by the prior art.

I claim as my invention:

1. In a guiding and centralizing device of the class described for wrapping machines, a pivoted lever, a weight movable therealong to different positions thereon, 85 rollers arranged in angled relation at the end of said lever to bear upon an article being wrapped, and means limiting the downward swing of said lever after an article has been removed from the machine.

2. A centralizing and guiding device for wrapping machines comprising a pivoted lever, roller means on the end thereof to bear upon the article adjacent the point of application of the wrapper thereon, and means adjustably mounted on said lever for varying the pressure with which said rollers bear upon the article.

3. A centralizing and guiding device automatically adaptable to articles of different size and inequalities in the surface of an article being wrapped in the wrapping machine, comprising an adjustably weighted pivoted lever, and roller means mounted on the end thereof adapted to bear upon the article substantially at the point of application of the wrapper by the machine.

4. In a device of the class described, a pivotally mounted bracket, a roller rotatably mounted thereon adapted to bear on the article being wrapped, rollers rotatably mounted on the bracket angularly directed with respect to the aforesaid roller to engage the article wrapped therebetween, and adjustable means for varying the pressure of the rollers on the article wrapped.

5. In a wrapping machine of the class described, a centralizing and guiding device therefor comprising a pivoted lever, adjustable weighted means suspended therefrom for varying the gravitational effect on said lever, rollers on the outer end of said lever, and means limiting the downward movement of said lever.

6. In a centralizing and guiding device of the class described adapted to bear upon the periphery of articles mounted in a wrapping machine, pivoted means having notches therein, contact means on the end thereof

adapted to bear upon the article, mechanism limiting the downward movement of said pivoted means, and means adapted to engage in any one of said notches for varying the pressure of the contact means on the article.

5 In testimony whereof I have hereunto

subscribed my name in the presence of two subscribing witnesses.

FRANK M. PIERCE.
